UNITED STATES PATENT OFFICE

2,471,960

CONDENSER

Bernard C. Johnson, Mundelein, Ill., assignor to
Houdaille-Hershey Corporation, Detroit, Mich.,
a corporation of Michigan

Application August 14, 1944, Serial No. 549,437

5 Claims. (Cl. 257—36)

1

This invention relates to heat exchangers made of sheet material and having turned-out fins to increase the radiating areas thereof.

Specifically, the invention relates to sheet metal condensers which are adapted to be mounted on the back of a refrigerator box to cooperate therewith in forming a stack for the passage of air therethrough.

The invention will hereinafter be specifically described as embodied in a sheet metal condenser unit for mechanical refrigerators, but it should be understood that the principles of this invention are broadly applicable to heat exchangers composed of sheet material, and the invention includes, within its scope, all uses of the sheet units.

In accordance with this invention, two metal sheets are secured together to define therebetween circulating ducts for fluids such as refrigerant. One of the sheets has flanges turned out therefrom adjacent the ducts to increase the heat dissipating area of the assembly. One of the sheets is shaped to provide side walls and mounting flanges, so that the resulting unit is readily attachable to the back wall of a refrigerator box to cooperate therewith to define a stack.

The turned-out flanges provide fins which materially increase the heat-dissipating area of the unit of this invention without increasing the amount of sheet metal used to form the unit. Because of the increased heat dissipating area, the units of this invention can be economically made from a minimum amount of material.

Condenser units of this invention give better control of refrigerant in mechanical refrigerator units, since they can be made smaller because of their efficient heat transfer capacity and need not maintain therein the larger amounts of refrigerant heretofore retained by condenser units. The smaller units of this invention condense the refrigerant at a fast rate and refrigerators using these units need not have as much refrigerant as was heretofore considered necessary.

It is, then, an object of the present invention to provide heat exchangers of sheet material having increased heat dissipating or absorbing areas without requiring added amounts of sheet material.

A still further object of the invention is to provide a sheet metal heat exchanger with turned-out flanges cut from a sheet of metal forming the body of the heat exchanger and serving as radiating fins to increase the efficiency of the unit.

2

A specific object of the invention is to provide a stack type sheet metal condenser with heat dissipating fins without adding metal to the condenser.

5 A still further object of the invention is to provide a stack type sheet metal condenser for refrigerators composed of a body sheet and an embossed sheet wherein the embossed sheet has turned out flanges adjacent the embossments thereof forming heat dissipating fins which materially increase the efficiency of the unit.

10 Another object of the invention is to add heat radiating surfaces to sheet metal heat exchangers without adding metal or other material to the exchangers.

15 A still further object of the invention is to increase the efficiency of heat exchangers about 40 to 50% without adding additional material to the exchangers.

20 Other and further objects of the invention will be apparent to those skilled in the art from the following detailed description of the annexed sheet of drawings which, by way of preferred example only, illustrates one embodiment of the invention.

25 On the drawings:

Figure 1 is a side elevational view of a refrigerator box equipped with a stack type condenser according to this invention.

30 Figure 2 is an inside broken plan view of the stack type condenser shown in Figure 1.

Figure 3 is a transverse cross-sectional view taken substantially along the line III—III of Figure 2.

35 Figure 4 is a perspective view of a portion of the inner sheet of the condenser, illustrating the manner in which it is sliced to provide the turned-out fins.

40 Figure 5 is a perspective view of a portion of the condenser illustrating the turned out flanges on the inner sheet forming heat-dissipating fins adjacent the ducts embossed on the inner sheet.

45 As shown on the drawings:

In Figure 1 the reference numeral 10 designates generally a stack type sheet metal condenser mounted on the back wall of a refrigerator box 11 by means of rivets 12 or other fastening means.

50 As best shown in Figures 2 and 3, the condenser 10 is composed of an outer sheet of metal 13 and an inner sheet of metal 14. The outer sheet of metal 13 provides the body for the condenser, and has side walls 13a, 13a extending at right angles to the main portion of the sheet 55 along the sides of the sheet. These side walls

have outturned flanges 13b on the ends thereof. The flanges are apertured as at 13c at spaced intervals along the length thereof to receive the rivets 12.

The sheet 14 is of less width than the sheet 13 and fits freely between the side walls 13a, 13a thereof. This inner sheet 14 has an embossment 15 along one marginal side portion thereof equipped with an inlet port 16 at its lower end and having a horizontal top leg 15a with two branches 15b depending therefrom.

The sheet 14 is embossed along its length to provide a plurality of banks of ducts 17. Three such banks are shown in Figure 2, but any number of banks can be used, depending upon the length of the unit.

Each bank 17 has a plurality of vertical embossments 17a connected at their top ends by horizontal embossments 17b and connected at their bottom ends by horizontal embossments 17c. The branches 15b on the leg 15a of the embossment 15 merge into the top horizontal embossment 17b of the top bank 17.

A plurality of vertical embossments 18 connect the bottom embossments 17c of the top bank 17 with the top embossment 17b of the next lower bank 17. A similar set of embossments 18 connect the middle and bottom banks 17.

The bottom embossment 17c of the bottom bank 17 has an embossment 19 depending from the mid-portion thereof. This embossment 19 has a tube receiving port 20 at its bottom end.

Refrigerant from the mechanical refrigerator unit of the box 11 enters the condenser unit 10 through the inlet port 16 of the embossment 15 and flows through the duct provided by the embossment into the top of the top bank 17 where it is distributed by the duct provided in the top embossment 17b through the vertical ducts provided in the vertical embossments 17a. The refrigerant flows downwardly through the banks 17 and through the ducts in the connecting embossments 18 to the duct in the embossment 19. Condensed refrigerant is removed from the condenser 10 through the outlet port 20.

The inner sheet 14, as best shown in Figure 4, is cut or sliced between the embossments 17a along top and bottom horizontal lines such as the illustrated top line 21, and also along a vertical line 22 intermediate the ends of the horizontal lines 21. The horizontal lines 21 are spaced slightly from the embossments 17b and 17c of each bank 17 as shown in Figure 2. The vertical line 22 is midway between each vertical embossment 17a as shown in Figure 4.

The lines of cuts 21 and 22 outline localized body portions of the sheet 14 and, as best shown in Figure 5, these localized body portions are turned at right angles to the sheet 14 to form heat dissipating fins 23. Thus a pair of heat-dissipating fins 23, 23 is formed between each embossment 17a. The outer sheet 13 is uncut and covers the space between the turned-out fins 23. The fins 23 project inwardly from the sheet 14 to lie in the air path A of the stack provided by the unit 10 as best shown in Figure 3.

The fins 23 increase the heat dissipating area of the entire condenser 10 by about 40%, and actually increase the heat dissipating area in the region of the banks 17 by more than 50%. Thus, as illustrated in Figure 5, each turned out fin 23 has two broad faces 23a and 23b extending away from the uncovered face 13d of the outer sheet 13. The two broad faces 23a and 23b of each fin 23 are added heat dissipating areas obtained

without sacrifice of any previous heat dissipating face, since the fins uncover a face 13d which would be covered if the fins were not turned inwardly. This increased heat dissipating area has been obtained without addition of metal.

The units of this invention are readily made from flat sheets of metal. The sheet 14 is cut along the lines 21 and 22, is embossed to provide the above-described embossments, and is stamped 10 to turn out the fins 23 from the body portions defined by the cuts 21 and 22. The sheet 13 is brazed, welded, or otherwise integrally bonded to the sheet 14 along the contacting areas of the sheets. The brazed-together sheets can then be bent on a mandrel to provide the side walls 13a and flanges 13b on the sheet 13.

The units 10 of this invention are inexpensive and, because of their increased efficiency, can be made with less metal or other sheet material than was heretofore required.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

30 A heat exchanger comprising a pair of secured-together contiguous metal sheets, one of said sheets being embossed to define between the sheets a plurality of spaced ducts, said one embossed sheet being sliced between adjacent ducts to provide a set of cuts defining a pair of localized body portions between each duct with each body 35 of the pair having an edge formed by a common line of cut, each localized body portion of the pairs being bent away from each other and from the other sheet to expose both faces of both 40 sheets and to form fins on the heat exchanger, and the other of said sheets being uncut and shaped to provide a space and a support for the heat exchanger.

45 2. A condenser adapted for cooperating with a refrigerator box to form a stack which comprises a sheet of metal shaped to form a back and side walls of a stack, a second sheet of metal integrally bonded to said first mentioned sheet along the inner face of the back wall portion thereof, said second sheet being embossed to cooperate with the first mentioned sheet for forming between the sheets a plurality of ducts, and said second sheet having sets of cuts adjacent said ducts, each of said sets defining a pair of local 50 bodies on the second sheet with the bodies of each pair having an edge defined by the same cut, said bodies being bent at substantially right angles to the second sheet to position said edges away from each other thereby exposing both 55 faces of both sheets and providing fins extending into the stack.

60 3. A stack-type condenser unit for refrigerator boxes and the like which comprises a sheet metal body having a back wall and side walls arranged to coact with the wall of a refrigerator box to define a stack, a second metal sheet integrally bonded to the inner face of the back wall of said sheet metal body, said second sheet being embossed and cooperating with the other sheet to define a plurality of spaced vertical refrigerant 65 circulating ducts, and said second sheet having between each vertical duct a vertical cut with horizontal cuts at the ends thereof, said vertical and horizontal cuts each forming a pair of local 70 body portions each with an edge defined by the 75

same vertical cut and with ends defined by portions of the horizontal cuts, and said local bodies being bent at an angle relative to the sheets for exposing both faces of both sheets and for forming fins projecting away from the sheets and into the stack.

4. A stack-type sheet metal condenser unit for mechanical refrigerators and the like comprising inner and outer secured-together contiguous metal sheets, the inner sheet being embossed to have a plurality of spaced superimposed banks of refrigerant-circulating ducts with each bank having a plurality of parallel ducts joined at their ends by header ducts, the inner sheet being sliced between each parallel duct of the banks of ducts and having localized body portions formed by the slices, said body portions being bent relative to the inner sheet to form fins for increasing the heat-dissipating area of the unit, and said outer sheet forming the body of the unit and being shaped to coact with a refrigerator box or the like for defining a stack.

5. A stack type sheet metal condenser unit for mechanical refrigerators comprising an outer sheet of metal bent to form a back wall, side walls, and outturned mounting flanges on the ends of the side walls, an inner sheet integrally bonded to the inner face of said back wall of the outer sheet, said inner sheet having an inlet embossment extending along one marginal side edge portion of the inner sheet with a top leg portion extending across the upper end of the inner sheet together with a plurality of banks of embossments

composed of spaced parallel vertical sections and transverse top and bottom connecting sections, the top bank having the top transverse section communicating with the top leg of the inlet embossment, and the bottom and top legs of the banks being connected through a plurality of vertical embossments, said inner sheet having a vertical cut between each vertical embossment of each bank and horizontal cuts between the top and bottom transverse sections of each bank of embossments, said cuts defining localized body portions, said localized body portions being bent at an angle to the inner sheet to expose the inner face of the back wall and to form fins for the unit, and said bottom transverse section of the bottom bank having a dependent outlet embossment in communication therewith.
